UNITED STATES PATENT OFFICE

2,473,748

PORTABLE MOLD FOR CONCRETE BLOCKS

Edwin F. Green, Ashland, Ky.

Application July 8, 1947, Serial No. 759,571

3 Claims. (Cl. 25—121)

1

My invention relates to improvements in portable molds for making concrete building blocks.

The primary object of my invention is to provide a simple form of easily handled, portable mold especially designed for easy and fast molding of concrete building blocks one at a time and for stripping the mold of the block without lifting the block.

Another object is to provide a mold of the character and for the purpose above set forth in which the molding of successive blocks may be accomplished with the use of a single pallet.

Still another object is to provide a mold for the purpose above set forth which is simple in construction, durable while light in weight, and inexpensive to manufacture.

Other and subordinate objects, also comprehended by my invention, together with the precise nature of my improvements, and the advantages thereof will be readily understood when the succeeding description and claims are read with reference to the drawings, accompanying and forming part of this specification.

In said drawings:

Figure 1 is a view in perspective of my improved mold in a preferred embodiment thereof positioned upright for filling with concrete, cement, or the like;

Figure 2 is a view in transverse section with the mold shown in broken lines partly rocked over preparatory to stripping;

Figure 3 is a view in longitudinal section taken on the line 3—3 of Figure 2;

Figure 4 is a view in transverse section showing the mold completely rocked over into inverted position and lifted to strip the same;

Figure 5 is a fragmentary view in vertical section taken on the line 5—5 of Figure 4 with the molded block eliminated;

Figure 6 is a view in longitudinal section taken on the line 6—6 of Figure 3 and drawn to a larger scale.

Referring to the drawings by numerals, the mold of my invention, as illustrated, comprises a rectangular mold box 1 of proper size for molding the usual concrete building block, and which is formed of light strong material, preferably aluminum, with side plates 2, end plates 3, a bottom pallet plate 4 and a pair of hollow cores 5, spaced apart and from the end plates 3 in the longitudinal center of said box and having closed upper ends. Outstanding, projecting flanges 6, 7 extending along the top and bottom edges of the side plates 2 reinforce said edges, and ribs 8 extending along the end edges of said plates 2 re-

2

inforce the same. A longitudinal, external reinforcing rib 9 is also provided on each side plate 2.

Side pairs of short legs 10 depend from the bottom edge flanges 7 and are spaced from the ends of said side plates 2 with bosses 11 above the legs on said plates 2, and flanges 7, reinforcing said legs.

A pair of cross bars 12 extend between the legs 10 upon opposite sides of said box 1 with downturned ends 13, welded or otherwise suitably connected to said legs, said bars 12 supporting the pallet plate 4 and the cores 5 which are suitably fixed to lugs 14 upstanding from said bars 12.

The pallet plate 4 is suitably apertured, as at 15, to fit over the cores 5 and is fitted between the side plates 2 and end plates 3 to slide into and out of said box 1 for a purpose presently seen.

The end plates 3 are slidably fitted in transverse grooves 16 in the ends of the side plates 2 to be slid into place and to slide outwardly of the open top of the mold box 1 when said box is inverted. The purpose of this will presently appear. Outstanding, upper corner stop lugs 17 at the ends of top edge reinforcing ribs 18 on said

end plates 3, and which seat on stop lugs 19 on the ribs 8 prevent sliding of said end plates 2 downwardly out of place while the mold box 1 is upright. Headed tie rods 20 extend across the ends of the mold box 1 with ends slidable through

ears 21 on said ribs 8, said rods being adapted for engagement by lateral bottom edge stop lugs 22 on the end plates 3 to limit sliding of said end plates outwardly of the top of the mold box 1 when said box is inverted. Wing nuts 23 threaded on one end of said rods 20 serve to draw the side plates 2 together to bind the end plates 3 in the grooves 16 and the pallet plate 4 between said side plates 2.

A tamping block 24, of any suitable material, such as wood, is provided to fit over the top of the mold box 1 and close the same.

A pair of arcuate rockers 25, of T-iron form in cross section, but preferably formed of aluminum, are bolted, as at 26, at one end thereof to the legs 10 on one side of the mold box 1 to extend crosswise of said box with the other ends 27 thereof projecting above the top of said box to form abutments against which the tamping block 23 may be placed to align said block with the top of said box. Tangential legs 28 on said rockers 25, adjacent the ends 27 thereof, are bolted, as at 29, to the adjacent side plate 2 to additionally secure said rockers 25 to said mold box 1.

Referring now to the use of the described in-

40

45

50

vention. With the wing nuts 23 tightened, to bind the end plates 3 and pallet plate 4, in place, and the mold box 1 stood upright on a suitable bench, or the like, not shown, so that the rockers 25 are positioned on the side of the mold box opposite to that facing the user of the box, said box 1 is filled with concrete, or cement, material and tamped with the tamping block 24. After the material has been tamped and leveled off, the tamping block 24 is left in place on top of the mold box 1 with one side edge abutting the upper ends 27 of the rockers 25. After the material has set, the mold box 1 is grasped at the ends thereof, by the hands, and rocked over onto the rockers 25, as shown in broken lines in Figure 2, while the fingers hold the tamping block 24 in place and resting on the ends 27 of said rockers 25. The mold box 1 is then rocked on the rockers 25 into inverted position with the tamping block 24 resting on the bench, not shown, and the mold box 1 resting on said block in inverted position. The wing nuts 23 are next loosened to loosen the side plates 2, end plates 3, and the pallet plate 4, and said box lifted by means of the tie rods 20 to strip the molded material, or block 30, as shown in Figure 4, from the mold box 1. In this stripping operation, the end plates 3 slide downwardly out of the mold box 1 until the stop lugs 22 engage the tie rods 20 and thereby guide said box against the molded block 30 while said box is being lifted, and also guide the pallet plate 4 to slide out of the mold box 1 with the molded block 30. After the mold box 1 has been lifted sufficiently for the end plates 3 to clear the molded block 30, and the pallet plate 4, said box may be set back into upright position on the bench. This will cause the end plates 3 to drop back into place, under the influence of gravity, after which the pallet plate 4 may be lifted off the molded block 30 and replaced in said mold box 1. Then the wing nuts 23 may be tightened to bind the end plates 3 in place, together with the pallet plate 4, in a manner which will be clear. The mold box 1 is now conditioned for refilling to mold another block. Another tamping block 24 may be used in proceeding with the molding of another block, or the same one used if desired after it has been cleared of the previously molded block 30. Obviously, the described rocking and lifting operations may be performed in substantially one continuous operation so that the device can be used quickly and easily, and stripping of the mold box 1 can be accomplished without lifting any appreciable weight whereby molding of successive blocks may be accomplished with ease and without tiring the user of the device.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claims.

Having described the invention, what is claimed as new is:

1. A mold box for building blocks adapted to be stood upright for filling with moldable material and to be stripped of molded material by inverting and lifting the same, a pair of rockers on one side of said box for rocking said box into inverted position for lifting inverted, and end plates in said box slideable partway out of the same when the box is lifted in inverted position to thereby guide lifting of the box relative to the molded material.

2. A mold box for building blocks adapted to be stood upright for filling with moldable material and to be stripped of molded material by inverting and lifting the same, a pair of rockers on one side of said box for rocking said box into inverted position for lifting inverted, end plates in said box slideable partway out of the same when the box is lifted in inverted position to thereby guide lifting of the box relative to the molded material, and means for binding said plates in said box against sliding operative to release said plates for sliding when said box is inverted.

3. A mold box for building blocks adapted to be stood upright for filling with moldable material and to be stripped of molded material by inverting and lifting the same, a pair of rockers on one side of said box for rocking said box into inverted position for lifting inverted, end plates in said box slideable partway out of the same when the box is lifted in inverted position to thereby guide lifting of the box relative to the molded material, and means for binding said plates in said box against sliding operative to release said plates for sliding when said box is inverted including end cross rods on said box providing hand holds for lifting the box.
